UNITED STATES PATENT OFFICE.

CHARLES S. BOARDMAN, OF PITTSBURGH, AND JOHN W. FREE, OF WOODLAWN BOROUGH, PENNSYLVANIA, ASSIGNEES TO JONES & LAUGHLIN STEEL CORPORATION, OF PITTSBURGH, PENNSYLVANIA, A CORPORATION OF PENNSYLVANIA.

JOIST HANGER.

Application filed March 23, 1926. Serial No. 96,835.

This invention relates particularly to metal hangers for light weight structural beams and so-called "metal lumber" joists, and aims to provide a positioning and supporting means for such beams and joists for connecting them to the girders and headers of a steel structure, and for supporting pipes and ducts and portions of the ceiling structure. A further object is to provide a light, 10 strong hanger which may be readily manufactured by commercial methods and easily installed without special tools, and which requires no drilling or preparation of the supporting structure or joist to receive it. 15 Further objects and advantages of the invention will appear from the description of the illustrative embodiments shown in the accompanying drawings, wherein

Fig. 1 is a side view and Figs. 2 and 3 a 20 plan view and end view, respectively, of a double hanger for supporting the abutting ends of two joists from an intervening I-beam, showing the joists and beam in place;

Fig. 4 is a side view of a single hanger 25 for use with a channel shape supporting beam or girder;

Figs. 5, 6 and 7 are views similar to Figs. 1, 2 and 3 of a modified form of double 30 hanger; and

Figs. 8 and 9 are plan views of spacing and securing clips used with these hangers.

Referring to Figs. 1, 2 and 3, the double 35 hangers illustrated therein comprises a pair of angle bars 10, disposed side by side and connected at their ends by two U-shaped straps 11. The angle bars may be placed across the top flange of a girder 12, with the strips disposed on opposite sides of the 40 girder and hanging down like stirrups in position to receive and support the adjacent ends of the steel joists 13. The upper ends of the straps are advantageously bent over the vertical flanges or legs of the angles, and 45 may be riveted or welded thereto in order to make them secure.

The horizontal flanges or legs of the angles are preferably disposed to face outwards, and are sheared or notched at their outer 50 edges to form two prongs 14, as shown in dotted lines in Fig. 1, which embrace the top flanges of the girder and serve to position the hanger thereon similarly to a saddle. These prongs 14 may be bent around under

the top flange to secure the hanger in position as shown and clamp it from movement lengthwise of the girder.

Spacing clips 15 are fitted over the lower or bearing portions of the U-straps to embrace them and fill the gaps between the 60 straps and web of the girder 12. These clips are held in place by the weight of the steel joists 13, the ends of which rest upon the clips and resist any tendency of the U- 65 straps to deflect inwards towards the girder under the weight of the joists.

The single hanger shown in Fig. 4 is designed for use with a channel girder, and comprises angle bars 16 with positioning prongs 17 cut from the horizontal flanges to 70 engage the top flange of the channel 18, and a stirrup 19 suspended therefrom with a spacing clip 20 to support the end of the steel joist 21. The single hanger may be designed for use with an I-beam support equally well 75 by lengthening the saddle portions of the angle bars 16 to suit the wider top flange of the I-beam.

The positioning or saddle prongs may 80 easily be bent to engage under the top flange by means of an ordinary hammer so as to secure the hangers in proper place lengthwise of the support to suit the desired spacing of the joists prior to raising the latter to position in the structure, so that the joists 85 may be permanently set as fast as they are raised to place. The joists need only to be cut to length before being set in place, and this may be done in advance of raising them, either in the shop or on the ground, as may 90 be most convenient.

In the hanger shown in Figs. 5, 6 and 7, the top supporting members 22 may be angle bars or other convenient shapes for supporting the stirrups 23, and are disposed with 95 their ends projecting over the supports 24 further on one side than the other, as shown in Fig. 6. The stirrups 23 are provided with notches 25 on their inner edges which are nearest to the supports 24 to embrace the top 100 flange thereof when in position to receive the joists 26. By twisting the hangers they may be dropped into position on the supports, and when turned into alignment with the joists the notches 25 will secure them in 105 place. Clips 27 (see Fig. 9) may be fitted to the stirrups to retain them in alignment and prevent their lower ends from being de-

flected towards the supports by the weight of the joists.

The use of the spacing clips 15, 20 and 27 enables a lighter section saddle bar to carry 5 the weight of the joists than would be safe without it, as thereby the saddle bars are relieved of bending stresses and it is only necessary to make them heavy enough to sustain the shearing stresses due to the vertical load upon the end of each joist.

A further advantage of these spacing clips is the ready means thereby provided for supporting the ceiling structure adjacent to the supporting girders, and for supporting pipes, 15 wires, electrical conduits, and other things that it is desired to install in the floor structure extending crosswise of the ends of the floor beams.

It is obvious that hangers embodying the 20 invention may be adapted to various types and dimensions of supporting members having top flanges, and may advantageously be used for supporting joists and beams of various types.

25 The invention is not restricted to the particular shapes shown, and may be adapted by change of one or two dimensions only to meet the usual conditions of service.

We claim the following as our invention.

30 1. A joist hanger or the like comprising a support, a saddle member arranged on said support, a stirrup member depending from the saddle member and secured thereto at its upper end, and a spacing clip carried by 35 said stirrup to prevent movement of said stirrup toward said support.

2. A joist hanger or the like comprising saddle members adapted to embrace the top flange of a supporting beam or girder member, a stirrup member suspended from the projecting ends of said saddle members and a clip embracing the stirrup member to 40 form a seat for the joist, said clip extending inwards towards the web of the supporting member.

3. In combination with a joist hanger for straddling a flanged beam having a web, and comprising a depending stirrup forming a support for the joist and spaced from the 50 web, a clip carried by the stirrup and engaging the web to prevent movement of the stirrup inwards toward the web under the weight of the joist.

4. In combination with a joist hanger for 55 straddling a flanged beam having a web, and comprising a depending stirrup forming a support for the joist and spaced from the web, a clip seated on the stirrup and engaging the web to prevent movement of the stirrup inwards toward the web under the

weight of the joist, said clip being retained in engagement with the stirrup by the joist.

5. A joist hanger or the like comprising saddle members adapted to engage the top flange of a supporting beam or girder member, stirrup members suspended from the projecting ends of said saddle members on opposite sides of the supporting member, and clips embracing the stirrup members to form seats for the joists, said clips extending inwards towards the web of the supporting members to form extensions of the lower flanges of said joists. 65 70

6. A joist hanger or the like comprising saddle members adapted to engage the top flange of the supporting beam or girder member, stirrup members suspended from the projecting ends of said saddle members on opposite sides of the supporting member, said stirrups having provision for engaging 80 said flange, and clips embracing the stirrup members to form seats for the joists, said clips extending inwards towards the web of the supporting members to form extensions of the lower flanges of said joists and prevent lateral or twisting movement of the hanger thereon. 85

7. In combination with a beam and transversely disposed joists supported therefrom at their ends, beam hangers comprising 90 saddle members straddling the joists and having stirrup portions depending from their extremities and spaced from the web of the beam, the ends of the joists being suspended thereby from the top flange of the beam and spaced from its web, and supporting members carried by said hangers in approximate alinement with the lower flanges of said joists and extending inwards 95 towards said web to enclose the spaces between the ends of the joists and the web of the beam. 100

8. In combination with a beam and transversely disposed joists supported therefrom at their ends, beam hangers having stirrup portions depending from their extremities and spaced from the web of the beam, the ends of the joists being suspended thereby from the top flange of the beam and spaced 110 from its web, and supporting members carried by said stirrup members in approximate alinement with the lower flanges of said joists and extending inwards towards said web to support portions of the floor in the spaces between the ends of the joists and the web of the beam. 115

In testimony whereof, we have signed our names to this specification.

CHARLES S. BOARDMAN.
